(57) **CLAIM**

The ornamental design for a tyre for vehicle wheels as shown and described.

DESCRIPTION

FIG. 1 is a perspective view of a tyre for vehicle wheels showing our new design;

FIG. 2 is a top view thereof;

FIG. 3 is a bottom view thereof;

FIG. 4 is a front view thereof;

FIG. 5 is a rear view thereof;

FIG. 6 is a left-side view thereof; and,

FIG. 7 is a right-side view thereof.

The broken line showing of the tyre for vehicle wheels is included for the purpose of illustrating portions of the tyre for vehicle wheels and forms no part of the claimed design.

1 Claim, 7 Drawing Sheets
